Patented July 4, 1967

208,018

HAIR BRUSH

Anthony Battaglia, 455 NW. 202nd Terrace,
Miami, Fla. 33162

Filed Oct. 17, 1966, Ser. No. 4,304

Term of patent 14 years

(Cl. D9—2)

FIG. 1

FIG. 2

FIG. 3

FIG. 4

FIGURES 3 and 4 are end views thereof taken from the right and left of FIG. 2, respectively.

The drawing is shaded to indicate contrast.

I claim:

The ornamental design for a hair brush, substantially as shown and described.
